UNITED STATES PATENT OFFICE.

MICHAEL RITNER, OF VINCENNES, INDIANA.

IMPROVEMENT IN PROJECTILES FOR ORDNANCE.

Specification forming part of Letters Patent No. 37,361, dated January 6, 1863.

To all whom it may concern:

Be it known that I, MICHAEL RITNER, of Vincennes, in the county of Knox and State of Indiana, have invented a new and useful Improvement in the Modes of Using Ordnance Projectiles; and I do hereby declare that the following is a full and exact description thereof, reference being had to the accompanying drawings, and to the letters of reference thereon, like letters in the several figures indicating the same or analogous parts.

Heretofore it has been considered impracticable to use lead as the material from which to form projectiles for ordnance, for the following among other reasons, to wit: First, the powerful explosion of a piece of ordnance tends to upset and distort the ball; second, the intense heat of the gases escaping from the rear of the ball and passing over the surface of the ball or projectile tends to fuse and cut away its surface.

It is manifest that if a leaden projectile become upset by the power of the explosion such effects will greatly detract from the accurate flight of the ball, and the melting of the surface of the leaden ball will not only detract from its capability for accurate and powerful shooting, but will leave a deposit of lead, more or less, upon the bore of the gun; but for these and other objections leaden projectiles for ordnance would be preferred over all others for cannon use, since to a given weight of metal, if of lead, a greater momentum can be imparted than if such weight were composed of iron or steel, and hence for ordinary purposes a greater accuracy in flight, greater range, and increased penetration would be attained; but, aside from the ordinary uses of ordnance projectiles, I have discovered that a leaden projectile can, for ordinary purposes, (and as I shall describe,) be used with great efficiency in the penetration, displacement, and battering down of iron or steel clad structures.

The experiments heretofore made in the use of leaden projectiles for ordnance have failed, owing to the causes stated, and the upsetting of the lead and the bursting of the gun and the absence of the knowledge of means to effectually prevent "windage" have permitted the heated gases to come in contact with the projectile during its passage from the gun, and thus

fuse and cut away its surface. By my invention these difficulties are overcome; and it consists in combining an ordnance projectile made of lead with a sabot or wad composed of vulcanized india-rubber or gutta-percha, or a combination of these.

Figure 1 is a perspective view of a leaden ordnance projectile, A, with a vulcanized rubber wad, B, applied to its rear end. The end of the wad which is intended to abut against the cartridge being made concave, as at C. Fig. 2 is a sectional view of Fig. 1. Fig. 3 is a perspective view of a projectile, the same as Fig. 1, but applied to a vulcanized-india-rubber wad, B', made with a central perforation, d, as shown, and having a conical plug, d', therein indicated, so that the action of the exploded powder may drive the plug d' into the perforation d, and thus expand the wad against the bore of the gun from which it is "fired." Fig. 4 is a sectional view of Fig. 3. Fig. 5 is a perspective view of a projectile, A, the same as in Figs. 1 and 3, but having a solid cylindrical wad, B², applied to its rear end, said wad being covered, as shown, with cotton or "duck" or woolen cloth or other fibrous material e, and which may be saturated with suitable lubricating substance. The wad B² may be composed of vulcanized india-rubber, or it may be composed of the substance known as "Ray packing," the main constituent of which is vulcanized rubber or gutta-percha and rubber combined and vulcanized.

In the several figures I have shown the leaden projectile A and the sabots B B' B² in the relative positions they will occupy with regard to each other when placed in a piece of ordnance and ready to be fired. It is apparent, then, that the shock of the explosion will be received in the first instance by the elastic sabot B, B', or B², as the case may be, and that the power of the gases will be gradually communicated, as it were, to the projectile through what may be termed an "elastic-cushion pressure," instead of a sudden blow. The ball or projectile A will thus be prevented from being upset or distorted by the action of the gases in forcing it from a state of rest. It is also apparent that the action of the gases upon the elastic sabot will be to expand its diameter and force its perimeter against all parts of the bore of the gun, and into the

grooves if the gun be grooved, and so afford perfect protection against windage; and this result is with the more certainty attained, since the rubber, being vulcanized, will resist the intense heat of the gases. The gases being kept from contact with the projectile in the act of firing, the leaden ball or projectile A is not subject to have its surface fused and cut away by them. It will thus be seen that by the simple combination of a leaden ordnance projectile with a vulcanized-rubber wad I am enabled to utilize ordnance projectiles which has heretofore proved a failure and attain results which cannot be attained by the use of iron and steel.

I find vulcanized-gutta-percha or a combination of gutta-percha with rubber will procure good effects. I therefore claim both rubber or gutta-percha or a combination of both.

I would here state that I do not wish to confine myself to the use of any particular form or construction of vulcanized-india-rubber or vulcanized-gutta-percha wads or sabots in combination with an ordnance projectile when made of lead and used in combination with vulcanized-india-rubber or vulcanized-gutta-percha wads or sabots.

Having now described my invention, what I claim as new, and desire to secure by Letters Patent of the United States, is—

The combination of a leaden ordnance projectile with a vulcanized-india-rubber or vulcanized-gutta-percha or a combination of vulcanized-india-rubber and vulcanized-gutta-percha wad or sabot, for the purpose set forth.

M. RITNER.
